GOLF GAME TARGET

Lawrence E. Cuttitta, New York, N.Y., assignor to
Manuel J. Bello, Lowell, Mass.

Filed Aug. 9, 1962, Ser. No. 71,214

Term of patent 14 years

(Cl. D34—5)

FIG. 1

FIG. 6

FIG. 2

FIG. 3

FIG. 4

FIG. 5

FIG. 1 is a top plan view of a golf game target showing my new design.

FIG. 2 is a view in elevation of the golf game target taken from the left hand side thereof.

FIG. 3 is a view in elevation of the upper end thereof.

FIG. 4 is a view in elevation of the golf game target taken from the right hand side thereof.

FIG. 5 is a view in elevation taken from the front thereof; and

FIG. 6 is a bottom plan view of the target, on a reduced scale.

I claim:

The ornamental design for a golf game target, substantially as shown.
